UNITED STATES PATENT OFFICE.

FRANK B. YARBRO, OF LOGANSPORT, INDIANA.

DESIGN FOR A SHOE-LACE FASTENING.

SPECIFICATION forming part of Design No. 34,479, dated May 7, 1901.

Application filed March 30, 1901. Serial No. 53,730. Term of patent 14 years.

To all whom it may concern:

Be it known that I, FRANK B. YARBRO, a citizen of the United States, residing at Logansport, in the county of Cass and State of Indiana, have invented and produced a certain new and original Design for Shoe-Lace Fastenings; and I do declare the following to be a full, clear, and exact description of the invention, such as will enable others skilled in the art to which it appertains to make and use the same.

The invention relates to a new and original design for shoe-lace fasteners; and it consists of a design of the configuration shown in the accompanying drawings, in which—

Figure 1 is a perspective view. Fig. 2 is an edge view, and Fig. 3 is an end view.

The leading feature of the design comprises an irregularly-curved plate 1, having an aperture 2, and a curved neck 3, having a T-²⁰ shaped head 4, the outer edge of which is rounded and the ends of which are bent upwardly to present a concave appearance to the head.

What I claim is—

The design for a shoe-lace fastener, as herein shown and described.

In testimony whereof I have hereunto set my hand in presence of two subscribing witnesses.

FRANK B. YARBRO.
